Edward D. Rapisarda, Agawam, Mass., assignor to Gilbert & Barker Manufacturing Company, West Springfield, Mass., a corporation of Massachusetts

Application October 4, 1954, Serial No. 32,519

Term of patent 14 years

(Cl. D52—2)

Fig. 2.

Fig. 1.

Fig. 3.

Fig. 1 is a front elevational view of a gasoline dispensing pump embodying my new design;

Fig. 2 is a side elevational view of the pump; and

Fig. 3 is a top plan view of the pump.

The rear of the pump is the same in appearance as the front and both sides of the pump are the same in appearance.

The dominant features of my design reside in the portion shown in full lines.

I claim:

The ornamental design for a gasoline dispensing pump, as shown and described.
